CLAIM

The ornamental design for a display stand, substantially as shown and described.

DESCRIPTION

FIG. 1 is a perspective view of a display stand showing my new design;
FIG. 2 is a side elevational view, the other sides being identical thereto; it is understood that the aperture pattern is continuous throughout the surface;
FIG. 3 is a top plan view thereof;
FIG. 4 is a bottom plan view of the cap; the stand removed for convenience of illustration;
FIG. 5 is a bottom plan view of the stand; and
FIG. 6 is a top plan view of the stand, the cap removed for convenience of illustration.
